UNITED STATES PATENT OFFICE.

AUGUSTE ALBERT HONORÉ TISSERANT, OF ST. CLOUD, FRANCE.

AIR COOLING SYSTEM FOR EXPLOSION ENGINES.

Application filed August 8, 1922. Serial No. 580,552.

To all whom it may concern:

Be it known that I, AUGUSTE ALBERT HONORÉ TISSERANT, a citizen of the French Republic, and a resident of St. Cloud, Department of Seine and Oise, France, have invented new and useful Improvements in an Air Cooling System for Explosion Engines, of which the following is a specification.

- 10 My present invention relates to air cooling systems for explosion engines, more particularly for engines with vertical cylinders serving to effect the propulsion of automobile vehicles, air craft and the like.
- 15 My improved system is of the type in which a fan driven by the engine and placed at the upper front part of the vehicle, delivers a current of air upon the cylinders, and in which a single casing, closed at its top and enclosing the upper part of the cylinders, is extended downwards by a separate sheath open at its lower end, enclosing the cylinders and in shape concentric therewith.
- 20 My invention has for object to obtain uniform cooling of the cylinders or groups of cylinders, by the arrangement employed for the supplying of the air delivered by the fan to the different cylinders of the engine, as well as for the circulation of the air along the outer surface of each cylinder.

25 My improved system of cooling is characterized by the provision of a casing entirely enclosing the fan delivering the air, of conduits of spiral shape integral with said fan casing, adapted to collect the total quantity of air, delivered by the fan, of lateral convergent passages arranged in continuation of said spiral conduits and adapted to lead the said air to the upper part of the cylinder casing, above the cylinders, and of a curved longitudinal wall carried by the upper cylinder casing, adapted to divert the air in a vertical direction downwards upon the cylinders, between the outer walls of the same and their cooling ribs and the separate sheath whose shape is concentric with the said cylinders.

30 The vertical cooling ribs are arranged

upon the outer wall of each of the cylinders along generatrices of the latter, in several groups of parallel ribs in each group, the ribs of each group being arranged at right angles to the ribs of the two adjacent groups, and each rib extending in a single plane without change of shape or section throughout the whole length of the rib.

35 This arrangement facilitates the circulation of air with a uniform speed over the whole extent of the cylinders and therefore ensures the desirable cooling of the latter, the passage ways between the ribs having throughout the same cross section, over the entire height of the cylinders.

40 Moreover, this arrangement of the cooling ribs facilitates the casting of the cylinders.

45 The annexed drawings represent by way of example a form of construction in which the invention is applied to a vertical four-cylinder engine.

50 Figure 1 is a side elevation, partly in vertical longitudinal section, showing the engine provided with the complete cooling system.

55 Figure 2 is a horizontal section upon the line 2—2 of Figure 1.

60 Figure 3 is a front elevation, partly in vertical transverse section upon line 3—3 of Figure 2.

65 Figure 4 represents on a larger scale a section upon line 4—4 of Figure 2.

70 Figures 1^a and 2^a are views corresponding substantially to Figures 1 and 2, showing a modification.

75 The cylinders *a*, with valves placed in the heads or ends at *a*¹, are provided externally with ribs *a*² arranged along the generatrices of the cylinders, that is, vertically; these ribs are divided into groups on each cylinder (see Figure 2), the ribs of one group being situated at right angles in relation to those of the adjacent groups. These ribs are continued beyond the cylinders proper, over their heads or ends, and are connected by welding or the like to the admission socket *a*³ and exhaust socket *a*⁴:

as a result of this arrangement the ribs provide a very large surface area, especially at the top or head of the cylinders, due to the sockets a^3 and a^4 , this being rational because the head forms the hottest part of the cylinders.

Moreover, this arrangement obviates the formation of any blind point at which the air would be pocketed and prevented from 10 circulating freely.

At the front and top of the engine there is provided a centrifugal fan b mounted in a casing, comprising a cylindrical portion c connected to two delivery passages c^1 c^2 15 of spiral shape. These passages c^1 c^2 are continued by two horizontal ones c^3 c^4 , converging laterally upon the centre line of the engine, at the top of the cylinders a , so as to direct the air discharged by the fan upon 20 the ends or heads of the cylinders.

The fan b , driven from the engine shaft d by a belt d^1 passing over pulleys d^2 and d^3 of suitable ratio, revolves in ball bearings mounted upon an axle b^1 which is itself 25 supported, at the front, by three arms b^2 b^3 b^4 and, at rear, by a transverse wall c^5 connecting the two passages c^3 c^4 .

The operation of the fan by means of a belt, in addition to the flexibility and smoothness of its working, allows the output of the fan to be always suited to the required cooling of the engine by driving the fan at 30 higher or lower speed.

The passages c^3 c^4 are cast integral with 35 a casing e of rectangular section enclosing the cylinder heads; this casing is likewise cast with the inlet and exhaust manifolds e^1 e^2 , and it is fixed by bolts e^3 to the flanges of the inlet and exhaust ports.

40 In the passages c^3 c^4 there are arranged, obliquely in relation to the direction of motion of the air-blast from the fan, transverse deflectors f f f , which divide the total quantity of air from the fan b in exact 45 proportion to each of the cylinders. The cover g , which closes the top of the casing, carries two longitudinal walls g^1 of curved shape, which constitute deflectors and compel the air currents, entering the casing e in 50 a horizontal direction through the two passages c^3 c^4 , to turn in towards the vertical axis of the cylinders and to circulate downwards along the ribs a^2 of the latter, firstly between the cylinder heads and the casing e , and then between the cylinders and an enclosing sheath h fitted to the casing e whose 55 shape conforms to that of the cylinders.

Owing to the double air-blast delivered by the spiral-shaped passages c^1 c^2 and the 60 continuation passages c^3 c^4 , the total quantity of air delivered by the fan is accurately divided into equal portions on either side of the cylinders; moreover, each of the two halves is divided by the transverse deflectors

65 f into equal fractions for the several cylinders. The air currents are directed by the deflectors g^1 firstly upon the valves, valve-chambers and cylinder heads, in such a manner that these parts and the valve-gear are always exposed to fresh cooling air, and 70 methodical cooling is thus attained. The ribs a^2 produce a rectilinear circulation of the air without eddies up to its point of exit at the bottom of the casing and sheath h , after it has absorbed the required amount 75 of heat.

On the other hand, as a result of the position of the fan at the top of the cylinders and its setting in the direction of forward travel of the vehicle, the fan is placed in the 80 best possible working conditions, especially as regards the power absorbed.

The arrangement of the diverting deflectors g^1 , upon the detachable cover g at 85 the top of the jacket-casing, allows by the removal of this cover ready access to the valves and valve-gear for inspection, cleaning and replacement when necessary.

As shown in Figures 1^a and 2^a, the pressure of the air-blast may be utilized for 90 supplying the carburettor; the casing e is extended at its rear end in the form of a pipe i which conveys a suitable quantity of air under pressure, delivered by the fan b , into the carburettor j connected by the inlet 95 manifold e^1 to the inlet valve ports.

This arrangement is especially applicable 100 to automobile and aeroplane engines of high speed; the carburettor being supplied with air under pressure ensures a proper inlet charge for the cylinders, whatever be the speed of running of the engine.

What I claim is:

1. In an air cooling system for explosion engines for propelling vehicles, comprising 105 an engine, a single casing closed at its top enclosing the upper part of the cylinders, a separate sheath forming a downward extension of said casing but conforming to the shape of the cylinders and being open at its lower end, vertical cooling ribs upon the cylinder walls, a fan driven by the engine and arranged at the upper front part of the engine, the combination of a casing entirely enclosing said fan, conduits of spiral 110 shape integral with said fan casing, adapted to collect the total quantity of air delivered by the fan, lateral convergent passages arranged in continuation of said spiral conduits and adapted to lead the said air to the upper part of the cylinder casing, above the cylinders, and a curved longitudinal wall carried by the upper cylinder casing adapted to divert the air in a vertical direction downwards upon the cylinders between the outer walls of the same and their cooling ribs and the separate sheath enclosing the said cylinders, for the purpose described.

2. In an air cooling system for explosion engines as claimed in claim 1, the provision of cooling ribs upon the outer wall of each of the cylinders along generatrices of the latter, arranged in several groups with the ribs in each group parallel, the ribs of each group being arranged at right angles to the two adjacent groups, and each rib extending in a single plane without change of shape or section throughout the whole length of the 10 rib for the purpose described.
- In testimony whereof I have signed my name to this specification.

AUGUSTE ALBERT HONORÉ TISSERANT.
